UNITED STATES PATENT OFFICE.

FRANKLIN R. WHITE, OF WATERBURY, CONNECTICUT, ASSIGNOR TO THE PATENT BUTTON COMPANY, OF WATERBURY, CONNECTICUT, A CORPORATION OF CONNECTICUT.

BUTTON.

Application filed March 23, 1922. Serial No. 545,923.

To all whom it may concern:

Be it known that I, FRANKLIN R. WHITE, a citizen of the United States, and a resident of Waterbury, in the county of New

5 Haven and State of Connecticut, have made and invented certain new and useful Improvements in Buttons, of which the following is a specification.

My invention relates to an improvement 10 in buttons and more particularly to that type or kind which is used with a staple having two prongs which are adapted to pierce their way through the bottom of the button and bend or upset against a die contained within the button; the object of the 15 present invention being to provide an article of this character which will comprehend a minimum number of parts, so that it shall be cheap to manufacture and assemble and 20 wherein the prongs of the staple are turned and upset directly upon the base of the button and thus do away with the usual holding anvil.

A further object is to accomplish the 25 aforementioned ends in a simple and expeditious manner and so construct the upsetting die which is contained within the button as to cause it to always remain fixed centrally within the button and thus be in 30 proper position to receive the prongs of the staple thereagainst and outwardly bend the ends thereof and upset them against the imperforate base, all of which go to make up a novel, as well as efficient and practical, 35 button.

With the foregoing and other objects in view, my invention consists in the improved button illustrated in the accompanying drawing and hereinafter described and 40 claimed, and in such variations and modifications thereof as will be obvious to those skilled in the art to which my invention relates, it being understood that changes may be made within the scope of what is claimed 45 without departing from the spirit thereof.

The preferred embodiment of my invention is disclosed in the accompanying drawings, wherein:

Figure 1 is a sectional view of a button 50 embodying the characteristic features of my invention and showing the parts as they are about to be secured to a garment or other material;

Figure 2 is a similar view showing the 55 button attached;

Figure 3 is a view in perspective of the novel form of upsetting die;

Figure 4 is a view in section taken on the line 4—4 of Figure 2; and

Figure 5 is a bottom plan view of the 60 body portion of my improved button.

Referring to the drawings, the body A of the button is provided with a downwardly extending hollow hub B and with an imperforate base C, the latter being provided 65 with a circular groove D adapted to receive the prongs E of the staple fastener F and guide them in their spaced relation through the metal of which the base C is formed.

Located within the body of the hub is the 70 upsetting die G, the same being composed of a head H and a base K, the head and base being substantially circular in outline and with the base somewhat larger in diameter and lying directly above the head, the two 75 parts being preferably composed of one piece of metal. The lower surface of the head H is provided with an annular groove L, causing the formation of a central conical member M. The base K of the upsetting 80 die is held in place by the button cap or top N and the adjoining portions of the body of the button, while the head of the upsetting die extends down within the hollow hub, 85 whereby the upsetting die is always held in proper position within the button and is also prevented from rattling.

The lower extremity of the upsetting die is accordingly located in close proximity to the base of the button and with the annular 90 groove of the die lying directly above the circular groove of the imperforate base of the button. With the parts as thus arranged, as the staple F is forced through the cloth or material O, the prongs E will 95 contact with the bottom of the circular groove D, pierce the metal, and upon passing therethrough will contact with the face of the upsetting die and the ends of the prongs will accordingly be bent outwardly 100 and upset, as shown in Figure 2, causing the prongs to bend downwardly upon and clinch against the upper surface of the base of the button and thus tightly secure the button to the cloth or material O. The button being thus formed of but few parts, is 105 accordingly simple in construction, will not rattle in service, and the active face of the upsetting die will always be in proper position with relation to the base of the button 110

so as to always cause the prongs of the fastener to be spread, upset and clinched against the inner surface of the base and thus insure the correct and secure attachment of the button.

Having thus described and explained my invention, I claim and desire to secure by Letters Patent:

A button of the character described comprising a body portion, a hollow hub and a base, a die comprising an enlarged base resting against the top of said button, and a relatively smaller concentric head project-

ing down within the hollow hub and lying directly above the base of the button, the lower surface of the die head and the base of the button provided with registering annular grooves.

Signed at Waterbury, in the county of New Haven and State of Connecticut, this 20 third day of March A. D. 1922.

FRANKLIN R. WHITE.
